United States Patent Office

Des. 232,707

Patented Sept. 10, 1974

232,707

VEHICLE FOR DISPENSING PETROLEUM PRODUCTS OR THE LIKE

Delles T. Davis, Abilene, and Bruce D. Motlong, Midland, Tex., assignors to Research Fuels, Inc.

Continuation-in-part of design application Ser. No. 24,449, Aug. 12, 1970. This application Nov. 11, 1971, Ser. No. 198,059

Term of patent 14 years

Int. Cl. D12—08

U.S. Cl. D12—14

Fig. 2

Fig. 4

Fig. 5

Fig. 6

FIG. 1 is a right side elevational view of a vehicle for dispensing petroleum products or the like showing our new design;

FIG. 2 is a left side elevational view thereof;

FIG. 3 is a rear elevational view thereof;

FIG. 4 is a top plan view thereof;

FIG. 5 is a bottom plan view thereof with portions omitted for ease of illustration;

FIG. 6 is a front elevational view thereof; and

FIG. 7 is an isometric view thereof.

This application is a continuation-in-part of our co-pending United States design application D. 24,449, filed Aug. 12, 1970 and now abandoned.

We claim:

The ornamental design for a vehicle for dispensing petroleum products or the like, substantially as shown and described.
